[57] **CLAIM**

The ornamental design for a pump tip for a soap dispenser, as shown and described.

DESCRIPTION

FIG. 1 is a lower-end and side perspective view of the design feature for a pump tip for a soap dispenser; the broken line depiction of a pump tip in this and other figures being for illustrative purposes only and forming no part of the claimed design;

FIG. 2 is an upper-end and side perspective view thereof;

FIG. 3 is an lower-end view thereof;

FIG. 4 is a left side view, the right side being a mirror image thereof;

FIG. 5 is a front view thereof; and,

FIG. 6 is a rear view thereof.
